SYNCHRONOUS CLOCK COMPRISING A
STRIKING MECHANISM

Hendrik Kinkhorst, Utrecht, Netherlands, assignor to N. V. Philips Gloeilampenfabrieken, Eindhoven, Netherlands

Application April 13, 1933, Serial No. 666,035
In the Netherlands April 18, 1932

2 Claims. (Cl. 58—38)

The present invention relates to a synchronous clock comprising a striking mechanism.

In the clocks driven electrically by means of a synchronous motor a spring is used for actuating the striking mechanism which spring after release is automatically wound up again by the motor. The clock is equipped with a number of separate wheels, levers and hammers forming the striking mechanism, which is operated at the appropriate moments by the normal driving mechanism of the clock.

The main object of the invention is to simplify the construction of such clocks in order that they may be readily manufactured in large quantities.

With clocks according to the invention the striking mechanism is directly driven from the synchronous motor. In an embodiment according to the invention the wheels of the normal traversing gear or at least some of them are simultaneously used for driving the striking mechanism so that the separate spring and wheels of the striking mechanism are dispensed with.

The principle underlying the invention holds good for clocks comprising striking mechanisms of different type, of which those provided with a toothed quadrant and with a recessed disc respectively are generally known.

Constructions furnished with this type of striking mechanism will be described hereinafter.

With a suitable form of construction of the invention, the minute wheel comprises two diametrically arranged pins cooperating with a lever which on being moved by the pins lifts the ratchet lever of the toothed quadrant or of the recessed disc thus releasing these members.

Hereinafter first of all a clock comprising a toothed quadrant striking mechanism will be considered. The pin wheel which cooperates with the toothed quadrant and by which the toothed quadrant is caused to resume its inoperative position upon striking of the clock is continuously driven from the motor shaft through a toothed gearing. The driving wheel mounted on the shaft of the pin wheel may be provided with one or more pins cooperating with levers secured to the shaft of the hammer of the chiming mechanism.

Furthermore, a second lever may be provided which is turned upon releasing the toothed quadrant and by which the hammer is brought into its active position shortly thereafter. Preferably an arm of the second lever is provided with an oblique surface against which the hammer shaft is pressed by means of a spring.

After the toothed quadrant has been released the hammer shaft is displaced shortly thereafter against the action of a spring due to the movement of the second lever. The levers for operating the hammer which are mounted on the shaft are actuated at each rotation of the pin wheel by the pins referred to of the toothed wheel mounted on the shaft of the pin wheel.

As the pin wheels of synchronous clocks rotate continuously it might occur that the toothed quadrant, when a comparatively large part of the quadrant representing consequently a relatively large number of teeth must drop—each tooth usually corresponds to one stroke—is prematurely caught by the pin wheel.

In order to avoid this drawback the periphery of the pin wheel may be furnished with an upstanding rim provided with one or more slits, whilst an elastic attachment is provided at the back of the toothed quadrant. This attachment, when the quadrant occupies its position of rest, lies between the pins of the pin wheel and the upstanding rim, consequently on the inner surface of the rim and moves through one of the slits upon disengaging the quadrant, thus always ensuring a sufficient time required for dropping before the quadrant is caught by the next pin of the pin wheel. For this purpose the pins and the slits must be given the correct position with respect to each other.

The above description substantially relates to clocks comprising a toothed quadrant striking mechanism. In the case of clocks having a striking mechanism comprising a recessed disc, a lever may be provided which is driven from the minute wheel and which on being moved relieves the recessed disc thus coupling the latter with the traversing gear by means of a coupling operated by said lever, which coupling preferably consists of a ratchet wheel with a pawl.

The invention will be more clearly understood by reference to the accompanying drawing representing by way of example, some forms of construction thereof.

Fig. 1 is a front view of part of the clockwork mechanism of a synchronous clock having a striking mechanism.

Fig. 2 is a side view of this part and Fig. 3 is a plan view thereof.

Referring to the drawing, the driving mechanism is arranged in a known manner between the frame parts 1 of the clock and comprises a synchronous motor 2 which drives the hour hand 3 of the clock through the intermediary of a toothed gearing. For the sake of clearness the

detailed construction of the driving mechanism between the motor and the hands has not been shown on the drawing. The minute wheel 4 is provided with two diametrically arranged pins 5 operating a lever 6 pivotally secured to the front part of the frame whereby lever 6 is reciprocated twice during each rotation of the wheel 4. Owing to this movement of lever 6, the end of arm 9 lifts a ratchet lever 7 thus disengaging a pin 24 from the teeth of a toothed quadrant 8 and allowing the quadrant to fall in a known manner over a given distance. As is well known this distance is controlled by the usual snail cam which is usually connected to the shaft of the hour hand. Thereupon the quadrant 8 is caused to resume its initial position by the pin wheel 10 during which movement the clock strikes the appropriate number of hours. The pin wheel 10 is constantly driven from the motor shaft through the intermediary of a toothed gearing. The wheel 11 of this toothed gearing is secured to the shaft of the pin wheel and is provided with one or more pins 12 which are brought into engagement with a lever 15 secured to the shaft 13 of the hammer 14 of the striking mechanism when the shaft 13 is moved into a position in which lever 15 lies in the path of the pins 12.

To the front side of the front part of the frame is secured a second pivoted lever 16 which, after release of the quadrant 8, is turned clockwise so as to enable the displacement of the shaft 13 of the hammer mechanism.

For this purpose the lever 16 is provided with an arm 17 having an oblique end surface 18 which bears against an end of the shaft 13 passing through the frame wall. Upon clockwise movement of the lever 16 after release of the quadrant the shaft 13 is moved forwardly by the action of a spring 19 bearing on the back part of the frame, so that the lever 15 enters into the path of the pins 12 of the toothed wheel 11. The hammer 14 is thereby lifted a few times in accordance with the number of teeth over which the quadrant 8 falls. The periphery of pin wheel 10 is provided with an upstanding rim 20 normal to the plane of the disc to which the pins 26 are secured. In the form of construction represented in the drawing the rim is provided with two diametrically arranged slits 21. From the back of the quadrant 8 an elastic pin 22 projects within the rim 20 of the pin wheel 10. After disengagement of the quadrant 8 the pin 22 moves through one of the slits 21, whereupon the quadrant falls over the determined distance. The slits 21 are provided directly behind the pins 26 in the direction of rotation of the pin wheel 10 so that after pin 22 has passed through the slit 21 it takes as long as possible before the next pin 26 engages the teeth of the quadrant.

In order to disengage the hammer mechanism when the quadrant 8 is returned to its upper position shown in Fig. 1, the shaft 13 must be displaced against the action of the spring 19. For this purpose the lever 16 is connected to the quadrant 8 through a rod 23 (see Figs. 1 and 2). At the end of the movement of the quadrant the rod moves the lever 16 counterclockwise, whereby the surface 18 moves over the end of the shaft 13, and moves same in axial direction against spring 19.

In the operation of the device, assuming the parts to be in the position shown in Fig. 1, one of the pins 5 of the minute wheel 4 will engage the end of arm 27 and rotate lever 6 counterclockwise whereby the end of arm 9 will disen-

gage, from the teeth of quadrant 8, the pin 24 secured to lever 7. Disengagement of pin 24 allows the quadrant 8 to fall down through a distance depending upon the number of strokes to be made, as soon as one of the slits 21 comes into the proper position to allow the pin 22 to pass therethrough.

The lever 7 remains in its upper position with pin 24 disengaged from the teeth of quadrant 8 as long as arm 27 is held up by pin 5. As long as the pin 24 is out of engagement with the teeth of the rack, quadrant 8 will drop each time it is raised in one tooth by the pins 26 of constantly rotating pin wheel 10, as a result of which the quadrant 8 will not be raised out of its lower position.

Furthermore, as long as arm 27 is held in its upper position by one of the pins 5, it remains in contact with the bottom of an extension 25 of lever 16 whereby movement of arm 17 in a clockwise direction and actuation of the hammer mechanism is prevented. A short time afterwards—and while quadrant 8 is still in its lower position—arm 27 is set free from pin 5, whereby lever 6 due to its own weight turns clockwise and arm 27 releases its support of lever 16 at the extension 25. During the clockwise movement of lever 6, arm 27 comes in contact with an outwardly extending portion 28 of lever 16 whereby arm 17 is moved clockwise. Due to this movement of arm 17, together with the oblique surface 18, spindle 13 is moved in an axial direction by spring 19, so that the arm of shaft 13 enters the path of pins 12 and the hammer mechanism is operated thereby.

When arm 27 leaves pin 5, lever 7 falls into its lower or ratcheting position whereby the quadrant 8 will be raised in one tooth increments by the pins 26 of pin wheel 10. As the quadrant 8 reaches its original upper position (as shown in Fig. 1) it rotates lever 16 counterclockwise by means of rod 23, whereby the oblique surface portion 18 moves shaft 13 axially against the compression of spring 19 so as to remove arm 15 from the path of pins 12; thus making the striking mechanism inoperative. The number of strokes will be determined by the distance through which the quadrant has fallen and is controlled by a snail cam in known manner.

It is evident that many variations of the construction of the device set out hereinbefore are possible without departing from the spirit of the invention. It is possible, for instance, to arrange the frame parts 1 at a smaller distance from each other, in which case the synchronous motor is placed behind the back part of the frame. Owing to this the depth of the clockwork is reduced.

What I claim is:

1. In an electric clock having hands; an electric driving motor; driving gearing between said motor and hands; and a striking mechanism; said striking mechanism comprising a rack, a pawl member to restrain the movement of said rack, a lever actuated by said driving gearing at predetermined intervals to make said member inoperative and to allow the rack to fall from its normal position and to make said rack operative again, a snail cam associated with the hour hand of the clock to limit the fall of said rack, a pin wheel directly driven from said driving gearing to return the rack to its normal position, a wheel driven from the driving gearing and provided with a plurality of pins, a hammer mechanism comprising an axially slid able member having an arm thereon, a spring acting on

said slideable member to move said arm into the path of said pins, and means actuated by said lever after said pawl member has been made operative again to allow said arm to be moved into 5 the path of said pins during the time the rack is being returned to its normal position, said means being made inoperative by the rack when the rack reaches its normal position.

2. In an electric clock having hands; an electric driving motor; driving gearing between said motor and hands; and a striking mechanism; said mechanism comprising a hammer mechanism, a rack having a projection thereon, a member to restrain the movement of said rack, a 10 lever actuated by said driving gearing at predetermined intervals to make said member in-

operative and to make said member operative again, a pin wheel constantly driven from the driving gearing to return the rack to its normal position and having an annular cam provided with two slits, said cam and slits acting on said projection to allow said rack to fall at predetermined intervals, a snail cam associated with the hour hand of the clock to limit the fall of said rack, and means actuated by said lever after said member has been made operative again to couple 15 the hammer mechanism directly with the driving gearing during the time the rack is being returned to its normal position, said means being made inoperative by the rack when the rack reaches 15 its normal position.

HENDRIK KINKHORST.
